Primary Examiner — Cathron Brooks*Assistant Examiner* — Sydney R Buffalow*(74) Attorney, Agent, or Firm* — Leighton K. Chong(57) **CLAIM**

The ornamental design for a bottle tether, as shown and described.

DESCRIPTION

FIG. 1 is a front perspective view of my new design for a bottle tether, showing an attachment loop coupled by a snap buckle to a tethered bottle retaining loop;

FIG. 2 is a right side view of the article shown in FIG. 1;

FIG. 3 is a left side view of the article shown in FIG. 1;

FIG. 4 is a top view of the article shown in FIG. 1;

FIG. 5 is a bottom view of the article shown in FIG. 1;

FIG. 6 is a perspective view showing the article in FIG. 1 in an intended environment of use (attached to the handlebar depicted in phantom line); and,

FIG. 7 shows the bottle tether in FIG. 6 detached from its attachment loop by its detachable snap buckle to be separately carried by a user (depicted in phantom line).
